A. R. HEATH.
AUTOMATIC TRAIN STOP.
APPLICATION FILED MAR. 31, 1913.

1,090,396.

Patented Mar. 17, 1914.

UNITED STATES PATENT OFFICE.

ALBERT R. HEATH, OF NORFOLK, VIRGINIA.

AUTOMATIC TRAIN-STOP.

1,090,396.

Specification of Letters Patent. Patented Mar. 17, 1914.

Application filed March 31, 1913. Serial No. 757,960.

To all whom it may concern:

Be it known that I, ALBERT R. HEATH, a citizen of the United States, residing at Norfolk, in the county of Norfolk, State of Virginia, have invented certain new and useful Improvements in Automatic Train-Stops; and I do hereby declare the following to be a full, clear, and exact description of the invention, such as will enable others skilled in the art to which it appertains to make and use the same.

The present invention is directed to improvements in automatic stops for trains, and has for its object to so construct a device of this character that it can be conveniently attached to a train pipe of a railway car.

A further object of the invention is to provide a device of this character so constructed that it will automatically apply the brakes when the car trucks leave the track and assume an abnormal position in relation to the car body.

A still further object of the invention is to provide an alarm which will be sounded in the car to notify the passengers that the trucks have left the tracks, so that they may grasp the seats or some fixed object in the car to prevent injury incident to the rolling over of the car.

With these and other objects in view, this invention resides in the novel features of construction, formation, combination and arrangement of parts to be hereinafter more fully described, claimed and illustrated in the accompanying drawing, in which:—

Figure 1 is a partial side elevation of a railway car showing the device in place thereon. Fig. 2 is a sectional view on line 2—2 of Fig. 1. Fig. 3 is a top plan view of the device. Fig. 4 is a sectional view on line 4—4 of Fig. 1. Fig. 5 is a similar view on line 5—5 of Fig. 2. Fig. 6 is a fragmentary perspective view of the coupling.

Referring to the drawing, the numeral 1 designates a car body having the usual trucks 2. Mounted beneath the car body, and in the usual manner is a train pipe 3 and brake cylinder 4, the same being assembled and operated in the usual manner.

The attachment comprises a coupling 5 which consists of a section 6 and right angle extension 7. Detachably engaging the opposite ends of the section 6 are nipples 8 which serve to connect the coupling 5 in the train pipe 3, it only being necessary, in applying the device, to remove a short section of the train pipe.

The outer end of the extension 7 is provided with a plurality of spaced lugs 9, the same being threaded upon their outer surfaces for engagement by the threaded lugs 10 formed interiorly of the cap 11. The cap 11 is readily attached to the extension 7, owing to the fact that the lugs 10 carried thereby can pass between the lugs 9 of the extension, and upon partially rotating said cap, said lugs will coact to prevent displacement of the cap. The cap 11 is provided with an extension 12 which is interiorly threaded for the reception of the bolt 13, the inner end of which is swivelly connected to the disk 14, said disk having its inner face provided with a suitable washer 15 which bears against the outer end of the extension 7 to prevent any escape of air from the train pipe.

Mounted in the extension 7 is a coil spring 16 which has its outer end bearing against the washer 15, said spring being held against displacement when the cap 11 is removed by the pointed end 17 formed upon the upper end of the rod 18. The pointed end 17 of the rod 18 engages between the helices of the spring 16, as clearly shown in Fig. 4.

Mounted upon the upper surface of the extension 7 is a valve casing 19, in which operates a spring pressed valve of any well known construction, and has its stem 20 projected from said casing, the purpose of which will appear later. Leading from the casing 19 and passing through the bottom of the car 1 is a pipe 21, said pipe having a vertical section 22 which can be placed at any suitable point in the car, and is provided with a whistle 23, of any well known construction.

The extension 12 is squared upon its outer end and for engagement with the socket 24 formed intermediate the ends of the arm 25.

The upper end of the arm 25 is provided with a clip 26 to which is connected the inner end of the wire cable 27 which passes over a pulley 28 supported by the bottom of the car. The outer end of the cable 27 is attached to the truck 2. A similar clip 29 is connected to the lower end of the arm 25 and is connected to one end of the wire cable 30, the other end of which being connected 10 in a similar manner to the other truck of the car (not shown).

The cables 27 and 30 are suspended with sufficient slack so that the usual rocking of the car body will not actuate the arm 25, 15 but should either one of the trucks leave the track, the cable connecting the same and arm 25 will be drawn taut, whereby the cap 11 will be partially rotated, and at which time the threaded lugs 10 carried by the cap 20 will disengage the lugs 9 of the extension 7, and pass through the spaces between the lugs 9 under the action of the coil spring 16 and air under pressure from the train pipe 3. which rushes through the coupling 5 as 25 soon as the cap 11 is displaced. To prevent loss of the cap 11 and arm 25 a chain 31 is provided, and flexibly connects the same as clearly shown in Fig. 2 of the drawing.

Fixed near the upper end of the arm 25 30 is a plate 32, the same being so bent as to provide a cam plate 33, the same being so positioned that when the arm 25 is rocked, owing to the truck or trucks leaving the track, said cam plate will engage the valve stem 20 and force the same inwardly, thereby allowing air from the brake system to pass through the pipes 21 and 22 to sound the whistle 23. It is of course obvious that the cam plate 33 will engage the stem 20 only 35 during the time previous to the disengagement of the cap 11 from the extension 7, but during which time a sharp blast has been sounded.

To prevent disengagement of the arm 25 40 from the squared end of the extension 12 a coil spring 34 is interposed between said arm and the head of the bolt 13, as clearly shown in Fig. 2.

A spring pressed pin 35 is connected to 45 the lower end of the rod 18 and has its outer end detachably engaged in a socket 36 formed in the lower end of the arm 25, said pin serving to prevent accidental rocking of the arm 25 due to the vibration it is subjected to during the travel of the car. It 50 will be noted that the upper end of the rod 18 is threaded in the extension 7 consequently the rod will be permitted to turn sufficiently so that the end of the pin 35 55 will disengage the socket 36 when the arm is rocked through the medium of either cable 27 or 30.

From the foregoing description it will be seen that should one or both of the

trucks leave the track that the cables 27 65 and 30 will be drawn taut, thereby rocking the arms 25 sufficiently to permit disengagement of the cap 11 from the extension 7, and that the air under pressure and coil spring 16 will blow said cap from the extension 7, thus reducing the air pressure in the system with the result that the brakes will be automatically applied and the train stopped. Further it will be noted that the whistle will be sounded during the 75 initial rocking of the arm 25 through the medium of the cam plate 33 and valve stem 20'.

What is claimed is:—

1. The combination with a train pipe and 80 car trucks, of a coupling connected to the train pipe and having a lateral opening, a cap carried by the coupling, an arm fixed to the cap, means connecting the trucks and arm for rocking the same to disengage the 85 cap from the coupling, as and for the purpose set forth.

2. The combination with a train pipe and car trucks, of a coupling in communication with the train pipe and having a lateral 90 opening, a cap carried by the coupling, an arm fixed to the cap, a whistle mounted in the car, a valve for normally cutting off communication of air from the train pipe to the whistle, cables connecting the trucks 95 and arm to rock the arm when the trucks leave the track, and means carried by the arm to operate the valve to open the same to permit air to pass from the train pipe to sound the whistle.

3. The combination with a train pipe and 100 car trucks, of a coupling connected to the train pipe and in communication therewith, a lateral extension formed upon the coupling, threaded lugs mounted upon the extension and being arranged in spaced relation, a cap having threaded lugs carried thereby for engaging the first named lugs to hold the cap upon the extension, an arm fixed to the cap, cables connecting the arm 110 to the trucks, said cables being operable to rock the arm when the trucks leave the track to partially rotate the cap to cause disengagement of said lugs, whereby air under pressure from the train pipe will dislodge 115 said cap, as and for the purpose set forth.

4. The combination with a train pipe and car trucks, of a coupling connected to the train pipe and in communication therewith, a lateral extension formed upon the coupling, a cap detachably connected to the extension, an arm connected to the cap, a valve casing mounted upon the extension, a whistle mounted in the car and having communication with the train pipe through the valve casing and coupling, a valve stem projected from the valve casing, a cam plate carried 125 by the arm, cables connecting the arm and

trucks to rock said arm when the trucks leave the track, said cam plate being adapted to engage the valve stem to open the valve to sound the whistle during the rocking of said arm, said arm also serving to rotate the cap so that the air under pressure from the train pipe will force the cap from engagement with the extension, there-

by reducing the pressure in the train pipe to apply the brakes. 10

In testimony whereof, I affix my signature, in the presence of two witnesses.

ALBERT R. HEATH.
